[57] **CLAIM**

The ornamental design of a container with closed front compartment, accessible rear compartment and indicia bearing dividing wall, as shown and described.

DESCRIPTION

FIG. 1 is a perspective view of a container with closed front compartment, accessible rear compartment and indicia bearing dividing wall showing my new design;

FIG. 2 is a top plan view of the container showing my design;

FIG. 3 is a front elevational view thereof;

FIG. 4 is a side elevational view, as viewed from the left side of FIG. 3, with the right side elevational view being a substantial mirror image thereof;

FIG. 5 is a rear elevational view thereof;

FIG. 6 is a bottom plan view thereof;

FIG. 7 is a cross-sectional view taken along 7—7 in FIG. 3 and showing the dividing wall separating the front and rear compartments; and,

FIG. 8 is a cross-sectional view taken along line 8—8 in FIG. 3 and showing the dividing wall separating the front and rear compartments.

The broken lines are for illustrative purposes only and form no part of the claimed design.
